UNITED STATES PATENT OFFICE.

JOSEPH C. FOX, OF SEATTLE, WASHINGTON.

SAW-SWAGING MACHINE.

No. 888,701.

Specification of Letters Patent.

Patented May 26, 1908.

Application filed October 4, 1906. Serial No. 337,491.

To all whom it may concern:

Be it known that I, JOSEPH C. FOX, a citizen of the United States of America, and a resident of the city of Seattle, in the county 5 of King and State of Washington, have invented certain new and useful Improvements in Saw-Swaging Machines, of which the following is a specification.

My invention has for its primary object, 10 the provision of a machine of the above type which will be of improved and simplified construction.

With the above and other objects in view, to be referred to in the following description, 15 the invention resides in the construction, parts and combinations of parts hereinafter described and succinctly defined in the appended claims.

In the accompanying drawing, in which 20 like numerals of reference indicate like parts throughout the several views: Figure 1 is a view in front elevation of my invention, parts being broken away. Fig. 2 is a vertical section taken on line 2—2 of Fig. 1. 25 Fig. 3 is a plan view, and Fig. 4 is a fragmentary side elevation.

Reference numeral 1 indicates a base 30 formed of a single casting, and provided with an integral bracket 2 adapted to be engaged by suitable fastening means, as shown, for securing the device in position.

Base 1 is provided with a recess 3, extending inwardly from its forward edge and having its mouth flared, as shown, whereby to 35 facilitate the insertion of the saw to be swaged, and communicating with this recess 3, at its inner end portion is a horizontal opening 4 in which the die 5 is mounted to slide.

40 The forward end portion of die 5 is approximately rectangular in cross section and has the beveled end 5', while the rear end portion of the die is circular in cross section and the end thereof affords a broad bearing 45 for the adjusting screw 6.

Related to the forward end of the die is a cam 7 having a shoulder 7', the same being formed on a shaft 8 rotatably mounted in the base. The means now employed for 50 rotating shaft 8 consists of a slotted arm 9 fixed thereon, a slotted lever 10 mounted to turn on a suitable pin or the like, as 11, fixed to the base at a point below a horizontal line passing through shaft 8, and a bolt 12 55 having a shoulder 12' bearing on arm 9 and threaded end portions passing, one through

the slot of arm 9 and the other through the slot of lever 10. On the projecting end portions of bolt 12 are nuts 12" adapted to be alternately tightened to hold the bolt to 60 movement with either arm 9 or lever 10, this depending on the movement desired to be imparted to arm 9 relative to that of the lever.

Reference numeral 14 indicates a fixed pin 65 projecting into recess 3 above the cam 7 and coacting with another pin 15 which is slidably mounted and projects into said recess from the opposite side thereof, for clamping the saw. A screw 16 is employed for adjusting pin 15. Screws 16 and 6 have their outer 70 end portions provided with heads of suitable angular contour to permit of their being readily grasped by a wrench (indicated by dotted lines in Figs. 1 and 3) for operation 75 thereof to effect the desired adjustment.

Reference numeral 17 indicates a gage for limiting the movement of lever 10, this, as now considered embodying a plate formed integral with base 1 and provided with a vertical series of openings 17' into which the stop 80 18, in the form of a pin, is adapted to be inserted.

In operation, arm 9 and die 5 are properly adjusted, then the saw tooth placed between 85 the beveled end 5' of the die and the cam 7 with the point resting against shoulder 7' of said cam. The saw is then clamped between pins 14 and 15 by adjusting screw 16 inwardly after which lever 10 is swung until it strikes 90 stop 18, thereby turning cam 7 so that it swages the tooth against the bevel end of the die. To release the swaged tooth, lever 10 is swung back to its normal position and screw 16 adjusted outwardly. 95

Having thus described my invention what I claim as new and desire to secure by Letters Patent of the United States of America, is:—

1. In a saw swaging machine, a base, a die 100 therein, a shaft in said base, a cam on the shaft coöperating with said die, a hand lever pivoted to said base and formed with a longitudinal slot, an arm longitudinally slotted and connected to said shaft, a bolt having a central shoulder and threaded ends 105 with said shoulder disposed between said lever and arm and its ends passing through said slots of the lever and arm so as to be capable of movement along the lengths of said slots, and nuts on the bolt ends to lock said 110 bolt to either the lever or arm.

2. In a saw swaging machine, a base, a die

therein, a shaft in said base, a cam on the shaft to coöperate with said die, a hand lever longitudinally slotted and pivoted to said base, an arm longitudinally slotted and connected to said shaft, and means projecting in said slots of the lever and arm capable of being moved along the lengths of said slots and of being rigidly connected to either said

arm or lever and loosely connected to the other.

Signed at Seattle, Washington this 17th day of September 1906. 10

JOSEPH C. FOX.
